UNITED STATES PATENT OFFICE.

THOMAS W. CARRICO, OF SAN ANTONIO, TEXAS.

VAULT OR CELL FOR OUTHOUSES.

SPECIFICATION forming part of Letters Patent No. 434,244, dated August 12, 1890.

Application filed August 22, 1887. Serial No. 247,547. (No model.)

To all whom it may concern:

Be it known that I, THOMAS W. CARRICO, a citizen of the United States, residing at San Antonio, in the county of Bexar and State of Texas, have invented certain new and useful Improvements in Vaults or Cells for Outhouses, of which the following is so full, clear, and exact a description as will enable others skilled in the art to which my invention app-

10 pertains to make and use the same, reference being had to the accompanying drawings.

This invention has relation to odorless dry 15 outhouses, but more particularly to the cells or vaults for use therewith; and it consists in certain novel features of construction, as will be hereinafter described, and particularly pointed out in the claims at the end of this specification.

In the accompanying drawings, illustrating 20 my invention, and in which similar letters of reference denote corresponding parts, Figure 1 is a sectional side elevation of an outhouse, showing the cell and a hopper and receptacle situated in position therein. Fig. 2 is a detail side elevation of the cell, showing it as situated above ground. Fig. 3 is a similar 25 view but showing the cell mounted upon rollers. Fig. 4 is likewise a similar view but showing the cell as made of a much greater 30 depth in order to have the receptacle situated entirely or nearly so beneath the ground. Fig. 5 is a top plan of the cell on xx of Fig. 4. Fig. 6 is a fragmentary section through the 35 wall of the vault, showing the lining of lath and plaster.

The object of my invention is to simplify the construction and lessen the cost of the vault or cell shown in one of my former patents.

Another object of my invention is to construct a vault or cell which will be water-tight and rain-proof, and which will retain all matter that may escape from leaky or defective barrels until the said matter can be gathered 45 up and carted away without in any manner soiling the premises and tainting the surrounding atmosphere.

The objects generally of my invention are to provide a cell or vault which, from its simplicity of construction and cheapness of manufacture, will readily recommend itself to the great masses of poor people using outhouses.

Referring to the drawings, A represents the vault or cell, which may be of any size, (determined by the number of receptacles it is to contain,) and which vault or cell is adapted to be inclosed by any suitable building A³. The bottom of this vault I will designate by the letter A² and the sides by the letter A'; and it is provided with a hinged door or cover 60 B at its rear extremity, the lower end of which rests against the upper extremity of the sides A'. The purpose of this door is to exclude the rain and sun from the said vault.

Within the building A³ is adapted to be 65 situated a hopper C, secured to a seat C², and a receptacle D, to which the said hopper is snugly connected by the tubular extension C', and which receptacle D is situated within the vault or cell A; but as these form no part of 70 my present invention they do not require a particular description herein.

The vault A may be formed of a slight depth and situated entirely above the ground, as shown in Figs. 2 and 3; but I prefer to excavate a sufficient depth in the ground to allow its top to project but one foot (more or less) above the top of the ground in order to protect the cell against storms, &c., as shown in Figs. 1 and 4.

This vault or cell is preferably made as follows: E represents an outer wooden casing, and F represents a plastering, preferably, of lath and cement, between which and the outer wooden casing a space G is left, which is adapted to be filled with a concrete filling, and the bottom of the vault is preferably made of concrete. It will thus be seen that if any of the excrement should escape from the barrels it cannot sink down into the floor, but will rest 90 upon its top in such a manner that it can be readily and easily gathered up and carted away. Cast or wrought iron pans or wooden cells with a lining of sheet metal may be used; or I may dispense with the laths F, and simply use the cement-plastering, without departing from the general spirit of my invention and without in any way interfering with its usefulness.

In Fig. 3 the cell is shown as situated entirely above ground and mounted upon wheels H, so that the said cell can be rolled out to a suitable place for cleaning or for any other purpose.

Having thus described the construction, objects, and advantages of my invention, what I believe to be new, and desire to secure by Letters Patent, and what I therefore claim, is—

- 5 A dry outhouse consisting of the combination of a vault made of impervious material and provided with wheels on its bottom, with a housing and an inclined cover secured above it at the rear and having a seat and hopper 10 in the house, and a receptacle D, located within

the vault and closely fitted to the mouth of the hopper, all constructed and combined to operate substantially as described.

In testimony whereof I affix my signature in the presence of two witnesses.

THOMAS W. CARRICO.
